US0D1003097S

(12) **United States Design Patent** (10) **Patent No.:** **US D1,003,097 S**
(45) **Date of Patent:** **** Oct. 31, 2023**

(54) **BARBECUE GRILL**

(71) Applicant: **Dongguan HaoHong Outdoor Products Technology Co., Ltd.**, Dongguan (CN)

(72) Inventor: **Mengwei Yan**, Dongguan (CN)

(73) Assignee: **Dongguan Haohong Outdoor Products Technology Co., Ltd.**, Dongguan (CN)

(**) Term: **15 Years**

(21) Appl. No.: **29/777,795**

(22) Filed: **Apr. 8, 2021**

(51) LOC (14) Cl. **07-02**

(52) U.S. Cl.
